UNITED STATES PATENT OFFICE.

JAMES F. MCELROY, OF ALBANY, NEW YORK.

DESIGN FOR A RADIATOR.

SPECIFICATION forming part of Design No. 23,339, dated June 5, 1894.

Application filed April 10, 1894. Serial No. 507,068. Term of patent 14 years.

To all whom it may concern:

Be it known that I, JAMES F. MCELROY, a citizen of the United States, residing in the city and county of Albany, State of New York, 5 have invented and produced a new and original Design for Electric Radiators, of which the following is a specification, reference being had to the accompanying drawings, forming a part thereof.

10 Figure 1 is a front elevation. Fig. 2 is a section, these two views being deemed necessary to fully illustrate my design.

The leading feature of my design consists in a radiator of the shape shown provided 15 with the lattice or filigree work placed near the upper curved portion of the radiator, immediately below which is a plain solid sur-

face. The ends of my radiator are curved. The front and back of my radiator are cut away near the bottom leaving an open space. 20

It will be noticed by the sectional view shown in Fig. 2, that the top of the radiator is curved upwardly toward the center, making it convex in form on the outside, and that each side of the radiator presents the same 25 general design.

What I claim as my invention, and desire to secure by Letters Patent, is—

The design for an electric radiator as herein shown and described.

JAMES F. MCELROY.
